DESIGN FOR A BOTTLE

Benjamin Lewis, New York, N. Y., assignor to Lionel Rothchild, Dallas, Tex.

Application December 14, 1945, Serial No. 124,735

Term of patent 14 years

(Cl. D58—9)

To all whom it may concern:

Be it known that I, Benjamin Lewis, a citizen of the United States of America, residing at New York, in the county of New York and State of New York, have invented a new, original, and ornamental Design for a Bottle, of which the following is a specification, reference being had to the accompanying drawing, forming part thereof.

In the drawing:

tle, i. e., a view looking up at the base of the bottle.

I claim:

The ornamental design for a bottle, as shown.

BENJAMIN LEWIS.
